UNITED STATES PATENT OFFICE.

FRIEDRICH KINN, OF NEW YORK, ASSIGNOR, BY MESNE ASSIGNMENTS, TO
ELIZA SANDERS, OF BROOKLYN, N. Y.

FAN.

SPECIFICATION forming part of Letters Patent No. 278,799, dated June 5, 1883.

Application filed February 28, 1883. (No model.)

To all whom it may concern:

Be it known that I, FRIEDRICH KINN, of the city, county, and State of New York, have invented certain new and useful Improvements 5 in Fans, of which the following is a specification.

This invention relates to improvements in spring-fans, or fans of that class in which the web of the fan is spread out or opened by a spring applied to the center pivot and one of the end plates of the web whenever said end plate is released from the handle; and the invention consists of a forked handle, to the ends of which is centrally pivoted a folding web provided 15 with end plates, one of which is retained in a sliding and spring-acted casing at the base of the forked handle, while the other is adapted to clear said casing. The end plates of the web are connected by a spring that engages a trans- 20 verse stay-pin of the pivoted center disks of web, so as to spread the web into open position whenever by the release of one of the end plates the connecting-spring is permitted to actuate the web.

25 In the accompanying drawings, Figure 1 represents a vertical transverse section of my improved fan, shown with the web in open position. Fig. 2 is a side view, partly in vertical section, of the fan with the web in closed position. Fig. 3 is a sectional end view of the fan closed, and Fig. 4 is a horizontal section on line $x x$, Fig. 1.

Similar letters of reference indicate corresponding parts. 35 A represents the handle of my improved fan, the upper part of which is forked, so that the space between the forked portion or casing can be utilized for receiving the folded web B. The web is made of radial plait or folds in the cus- 40 tomary manner in fans of this class. The folds at each end of the web are strengthened by end plates or leaves, $b b$, of wood, sheet metal, or other suitable material. The folds of the web B are held together by disks $d d$, that are cen- 45 trally pivoted to the outer end of the forked handle A, said disks being connected by fixed transverse pins $d' d'$, to which the end plates, $b b$, are applied. The end plates, $b b$, are made of different length, one being somewhat longer 50 than the other, both being engaged by a slid-

ing casing, C, at the base of the forked portion of the handle A, said casing being guided by a fixed transverse pin, e , in slots and a looped guide, e' , of the forked handle, and acted upon by a spiral spring, e^2 , interposed between the 55 pin e' and the base of the forked handle, as shown clearly in Figs. 2 and 3. When the casing C is drawn back away from the web of the fan, the shorter end plate, b , is permitted to pass clear of the casing and swing around 60 the center pivot of the web to the other side of the handle, by which motion the web is spread into open position. By returning the end plate the web is folded up again, it being engaged in either position by the sliding and 65 spring-pressed casing C, which forms the fastening device for the end plates, b . Both end plates, $b b$, are connected by a rubber or other spring, D, that extends first along one end plate, b , then between the disks $d d$, and along the 70 opposite end plate, b . The spring D is re- 75 tained between the center disks, $d d$, by a fixed transverse pin, located intermediately between the stay-pins $d' d'$ of the disks. The spring D serves to engage the pin f of the disks when- 80 ever the shorter end plate, b , is permitted to clear the casing C, so as to produce thereby the turning of the center disks and the opening of the web until the end plate arrives at the other side of the forked handle and is re-engaged by the spring-casing C. By the tension of the 85 spring D on the pin f it is carried with the center disks, $d d$, around the pivot-pin d' until the pin f arrives at a position below the pivot d' , but diametrically opposite to its former po- 90 sition above the same, as shown in Fig. 1.

The web B is held in open position by the action of the spring and the retaining action of the casing C. For closing the fan the shorter end plate, b , is released again from the casing 95 and swung around the pivot of the web until it arrives at the opposite side of the casing C, by which motion the spring D is expanded and the center disks, $d d$, with their transverse pin, returned to their normal position, as shown in Fig. 2. The fan is consequently thrown into open position with great facility by the action of the spring on the end plates, $b b$, and the center disks, $d d$, by simply releasing the shorter end plate by drawing back the casing 100

C and allowing it to re-engage the end plate when the web is opened, all of which is accomplished by the action of one hand, as the thumb and index-finger operate the casing, while the 5 remaining fingers take hold of the hand. For closing, the casing has to be drawn back and the web returned into folded position by taking hold of the end plate with the other hand.

I am aware that fans which are thrown into 10 open position by the action of a spring applied to the web and the center pivot of the same are old and well known. I am also aware that a forked fan-handle in which the web is pivoted to the outer end of the forked portion 15 and arranged with end plates, one of which is retained at the base of the forked portion, while the other is free to swing from one side to the other of the handle, to be then locked by fast-

ening devices of the forked handle, is also well known, and I therefore distinctly disclaim 20 these features.

Having thus described my invention, I claim as new and desire to secure by Letters Patent—

As an improvement in a fan, the combination of the disk and web with the elastic 25 spring-band D, the transverse stay-pin f, the end plates, b b, and the sliding casing C, substantially as described.

In testimony that I claim the foregoing as my invention I have signed my name in presence of two subscribing witnesses. 30

FRIEDRICH KINN.
